DESIGN FOR AN ARTICLE OF CROCKERY.

SPECIFICATION forming part of Design No. 14,136, dated July 31, 1883.

Application filed June 29, 1883. Term of patent 3½ years.

UNITED STATES PATENT OFFICE.

FERDINAND A. BENEDIKT, OF NEW YORK, N. Y., ASSIGNOR TO PAUL BENEDIKT AND MORRIS FRIEDMAN, OF SAME PLACE.

DESIGN FOR AN ARTICLE OF CROCKERY.

SPECIFICATION forming part of Design No. 14,136, dated July 31, 1883.

Application filed June 29, 1883. Term of patent 3½ years.

To all whom it may concern:

Be it known that I, FERDINAND A. BENEDIKT, of New York, in the county and State of New York, have invented a new and original Design for Articles of Crockery, of which the following is a specification.

10 This invention relates to a new ornamentation of the handles of articles of crockery.

In the photograph, the letter A represents an article of crockery, and B is its handle. This handle B is made to resemble a strap, and 15 has at its upper and lower parts buckle-like ornaments a and b. From the upper end of the handle extend along the sides of the article A strap-shaped wings C, which also have buckle-like ornaments d.

I claim—

1. The design for an article of crockery, the same consisting of strap-shaped handle having buckle-like ornaments a b.

2. The design for an article of crockery, the same consisting of the strap-shaped handle having buckle-like ornaments a b, strap-shaped wings C, and buckle-like ornaments d, substantially as shown.

FERDINAND A. BENEDIKT.
